ROBERT McCLENATHEN, OF CUYAHOGA FALLS, OHIO, ASSIGNOR TO KELLY-SPRING-FIELD TIRE COMPANY, OF AKRON, OHIO, A CORPORATION OF NEW JERSEY.

TRIMMING DEVICE.

1,408,016.

Specification of Letters Patent. Patented Feb. 28, 1922.

Application filed March 18, 1921. Serial No. 453,440.

To all whom it may concern:

Be it known that I, ROBERT McCLENATHEN, a citizen of the United States, residing at Cuyahoga Falls, in the county of 5 Summit and State of Ohio, have invented certain new and useful Improvements in a Trimming Device, of which the following is a specification.

The invention relates specifically to improvements for increasing the effectiveness of well-known trimming devices, characterized by co-acting disk knives in combination with a work pressing means, designed to trim irregularities, excess material and the like, from formed articles of manufacture, whereby the operation results in the reduction of the article to a pre-determined gage. The present disclosure, by way of illustration, shows the invention as applied to the 15 trimming of beads such as are used in the manufacture of pneumatic vehicle tires.

An object of the invention is to provide means on the peripheries of certain of the rotating disk cutters, whereby the article 20 passing through them, and in pressed engagement therewith, will be positively drawn into the cutting edges without lost motion due to slippage.

A further object is to provide an automatically operated pressure member, adapted to intermittently press upon and release the article being trimmed, the period of 25 oscillation being in synchronized relation with the trimming devices, whereby the pressure member will maintain contact with the article throughout the trimming period.

Another object is to provide a work support comprising means for securing angular adjustment thereof, and work centering 30 guides, whereby the operator is relieved of the duty of manually guiding the work through the cutters and of the incidental risk of injury to his hands.

The invention consists further in the certain novel features of construction and combinations of parts, more fully set forth in the specifications and claims and illustrated in the accompanying drawings.

In the drawings, which disclose one embodiment of the invention; similar numerals of reference denote corresponding parts.

Figure #1 is a longitudinal elevation of the device. The left hand element, which is a counterpart of the right hand side, is 55 shown in section.

Figure #2 is a transverse view taken at the mid-length of the bed, particularly showing the cam gear for operating the pressure guide wheel.

Figure #3 is a partial plan view of the 60 work support table, particularly showing the adjustable work centering rollers.

Figure #4 is an enlarged view showing the detail of the adjustable work centering 65 rollers.

Figure #5 is an enlarged view showing the co-acting disk cutters with a bead being trimmed thereby and retained by the pressure guide wheel.

Referring in detail to the drawings, the 70 invention is shown as applied to a machine comprising a base 1, and suitable supports 2. Journalized beneath the base is a power shaft 3, having on one end a pulley 4 on which a belt is run from any desired power 75 source. Near the extremities of shaft 3 are spur gears 5 keyed thereon and meshing with spur gears 6, which will be hereafter described.

Mounted on the bed 1 are a pair of aligned 80 housings 7 and 8, within which are contained the cutter disk spindles. In view of the fact that the mechanism related to these counterpart housings 7 and 8 is identical, except as otherwise noted, only those elements disclosed in housing 7 (Fig. #1) will be described. Provision is made by bolts 9 fitted in elongated slots 10 (Figs. #1 and #2) for bodily separating the housings in order to increase the gage between the cutting 85 edges of the disks.

Housings 7 and 8 are each bored to contain a pair of bushings 11 and 12, the upper bushing 11 being non-rotatable but axially 90 slideable within the housing and having journalized therein the upper knife spindle 13, the lower bushing 12 being non-rotatably keyed within the housing and having journalized therein the lower knife spindle 14.

Lower knife spindle 14 is provided with 100 an enlarged end 15 having a shoulder portion in engagement with a corresponding portion on bushing 12. On this end of the spindle is a removable disk cutter 16, having a cutting edge 17 and a portion 18 of the periphery knurled or otherwise roughened to maintain traction with the material being trimmed. (See Fig. #5.) The opposite end of the spindle 14 is keyed to the spur gear 6, which has an elongated sleeve por- 105 110

- tion 19, adapted to bear against the face of bushing 12. The extreme end of spindle 14, projecting beyond the gear 6, is provided with suitable lock nuts 20, which are used 5 to accurately adjust the spindle 14 within the bushing 12 in order that there shall be no longitudinal drift. This adjustment will be readily appreciated by reference to Fig. #1.
- 10 Upper knife spindle 13 is provided with an enlarged end 21 having a shoulder portion in engagement with a corresponding portion on bushing 11. On this end of the spindle is a removable disk cutter 22 having a cutting edge and adapted to register by suitable adjustment, with the cutting edge 17 of disk 16. The opposite end of spindle 13 is keyed to the spur gear 23, which has an elongated sleeve portion 24 adapted to bear against 15 the face of bushing 11. The extreme end of spindle 13, projecting beyond the gear 23, is provided with suitable lock nuts 25 which are used to accurately adjust the spindle 13 within the bushing 11 in order that there 20 shall be no longitudinal drift. (See Fig. #1.) Gear 23 being in mesh with gear 6, it is apparent that the spindles, with their respective disk cutters, revolve together in opposite direction.
- 25 In order that the cutting edges of disks 16 and 22 may be nicely adjusted and kept in contact, as wearing away and resharpening occur to increase the clearances, the entire spindle 13 is capable of longitudinal adjustment toward and away from disk 16. By reference to Fig. #1, it will be noted that the upper bushing 11 is axially slideable within its housing, the means being set screw 26 tapped into face plate 28 and bearing against the bushing, and draw bolt 27 tapped into bushing 11 and pulling against its head portion on the outer face of 28. Manipulation of these members 26 and 27 effect the desired object, it being noted that 30 the gear 23 can drift transverse of the wider face portion of gear 6 to compensate for the linear movement.
- 35 The work 47 being fed through the disks is pressed upon the knurled portion 18 of disk 16 by means of a pressure guide wheel 29, the operation being as follows. On shaft 3 is keyed a worm 30 driving a cam shaft 31 through a worm wheel 32. Shaft 31 is suitably journaled in bearings 33 and at one extremity mounts a grooved cam disk wheel 34 in which is cut a cam groove 35. Within this groove is confined a follower 36 attached to the end of a reciprocating arm 37, which passes up through the base 1 and is confined within a bearing 38. The upper portion of 40 37 is counterbored to house a floating link piece 39, which is confined therein, but free to move longitudinally within restrictions fixed by a pin 40 penetrating 39 and protruding from each side of an elongated slot 45 in arm 37. The upper end of 37 is provided with a collar 42 against which a helical spring 43 reacts; the lower end of said spring resting against the pin 40. It will thus be noted that the spring tends to keep 50 the end of link 39 pressed against the bottom of the counterbore in 37. Affixed to 39 is a connecting link 44 fashioned at its upper end into a clevis which is pinned to the oscillating arm 45. One end of arm 45 is fulcrumed at 46 to an upstanding bracket 58, the other end is formed as a clevis, or yoke, supporting thereon the free-running pressure guide wheel 29. (See Fig. #2.) On the up stroke of the cam gear the wheel 29 will 55 be raised from the work 47 by operation of the gearing mentioned, the lift being a positive operation due to the end of 39 bearing upon the bottom of the counterbore of 37. On the down stroke of the cam gear the 60 wheel 29 will follow by gravity the recession of link 44 until its periphery contacts with the work 47, at which point further movement of the wheel is, of course, arrested. After the wheel 29 has contacted with 47 65 the cam follower still seeks a lower position in the revolving cam groove 35, thus resulting in the compression of the spring 43 as arm 37 continues to recede while link 39, with its direct connected members, is arrested. The wheel 29 thereby resiliently presses 70 upon the work, causing it to adhere to the knurled surface 18 of disk 16 during the trimming operation.
- 75 The work support table 48 is pivoted on 100 suitable hinges 49 located on housing 8 in a convenient manner adjacent the contacting edges of a pair of cutter disks. Angular adjustment of the table to correspond with the contacting face of the work 47, as it lies 105 normally upon the disks 16, is effected by a telescopic brace 50, pivotally attached to the base 1 and table 48 and locked in any desired extension by means of a suitable clamp 51. Suitable guide rollers 52 are 110 journaled on pins in the free end of swinging arms 53 which extend upwardly within quadrant slots 54 in the table 48. The arms 53 are capable of being locked in any desired position by means of suitable wingnuts 115 55. In order that the guide rolls may be set to correspond with different diameters of the work, when in annular form, indicator points 56 are provided on the free end of arm 53 and in the table 48 are set graduated 120 scales 57 suitably laid off to the desired settings.
- 125 Having set forth the construction in such detail the operation of the device, as a whole, will be briefly described.
- It will be noted that this device is capable of continuous operation without requiring that the operator give his attention to duties other than the placing of a bead upon the table 48 and the removal of it therefrom 130

upon the completion of its single passage through the cutters; the operator having both hands free for the purpose of feeding. The gage width having been set between the 5 cutting edges, and the guide rollers 52 adjusted to accurately center a bead of the diameter being then trimmed, the machine is set in motion. As the pressure guide wheel raises automatically a bead is dropped upon 10 the table in proper relation with the guide rollers and is caught within the cutting edges of the disks. The pressure guide wheel now drops rapidly and confines the work within its shaped periphery, which corresponds 15 with the portion of the work contacted thereby. The wheel 29 is resiliently pressed upon the work, as explained, in a manner adapted to insure non-slippage of the work with respect of the knurled peripheries of the 20 lower disks 16. The cam gear is so designed that the period of contact of 29 with the work extends throughout one revolution of the work through the cutters, though any desired time may be set. At an appropriate 25 time the wheel raises rapidly, thus automatically notifying the operator that removal of the bead is in order. The cam gear is so arranged that the interval of release, that is, the time for removing a trimmed bead and 30 replacing a rough one, is reduced to the minimum.

As time is of the essence of commercial success of such a device as this, it will be appreciated that this invention has made the 35 trimming operation rapid and automatic, and that an operator has only to feed the machine, which is rated at a speed corresponding to his dexterity.

In the preferred form of this device a 40 tilting table has been shown on which the work is laid. The relative angular adjustment of this table with respect of the normal faces of the disks on which the work is pressed, may be secured by tilting the machine with respect of the table by means of appropriate adjustment and the same result 45 accomplished.

Having thus described my invention, I claim:—

- 50 1. A device of the character described comprising in combination, coacting disk cutters arranged in separated pairs, friction increasing means on one disk of each pair adapted to engage and draw the work 55 through the disks; and an automatically operated work pressure member adapted to intermittently press upon and release the work periodically in relation to the progress of the linear flow of the work through the cutters.
  - 60 2. A device of the character described comprising in combination, coacting disk cutters in spaced apart pairs, means associated with one cutter of each pair for regulating 65 the contact thereof with its coacting mem-
- ber, means for moving the spaced apart pairs toward and away from each other, a knurled peripheral portion on one disk of each pair; an automatically operated work pressure member in synchronized relation 70 with the disks, having means associated therewith for resiliently pressing said member upon and releasing it from the work.
3. A device of the character described comprising in combination, coacting disk cutters; a work pressure member in synchronized relation with the disk drive mechanism and adapted to intermittently press upon and release the work; and an inclined feed table having work centering means 80 thereon.
4. A device of the character described comprising in combination, coacting disk cutters; a work pressure member in synchronized relation with the disk drive mechanism and adapted to intermittently exert resilient pressure upon and release the work; and an angularly adjustable feed table having adjustable work centering means 85 thereon.
5. A device of the character described comprising in combination, coacting cutter disks, arranged in pairs, one disk of each 90 pair having a cutting edge and a friction increasing periphery; an automatically operated work pressure wheel adapted to intermittently grasp and resiliently press and release the work in synchronized relation with the cutter disk driving mechanism; and an angularly adjustable feed table having 95 adjustable work centering means thereon.
6. A device of the character described comprising in combination, coacting cutter disks, arranged in pairs, one disk of each 100 pair having a cutting edge and an elevated peripheral friction increasing part; an automatically operated work pressure wheel adapted to intermittently grasp and resiliently press and release the work in synchronized relation with the cutter disk driving mechanism; and a work holding table having 105 means associated therewith for securing relative angular adjustment between the face of the table and the normal work holding faces of the work support and cutting disks.
7. A trimming device comprising, coacting rotary disk cutters arranged in pairs, having friction increasing means on one 110 disk of each pair adapted to draw the work there through, an automatically operated work pressure means adapted to intermittently press upon and release the work periodically in relation to the progress of the 115 work through the disks, and a work support adapted to position and relate the stock to the disk cutters.
- 120 In testimony whereof I affix my signature.

ROBERT McCLENATHEN.
